UNITED STATES PATENT OFFICE.

THOMAS M. GALLAGHER, OF OLD ORCHARD, MISSOURI, ASSIGNOR TO SCULLIN-GALLAGHER IRON & STEEL COMPANY, OF ST. LOUIS, MISSOURI, A CORPORATION.

BOLSTER.

SPECIFICATION forming part of Letters Patent No. 698,928, dated April 29, 1902.

Application filed October 21, 1901. Serial No. 79,366. (No model.)

To all whom it may concern:

Be it known that I, THOMAS M. GALLAGHER, a citizen of the United States, residing at Old Orchard, in the county of St. Louis and State 5 of Missouri, have invented certain new and useful Improvements in Bolsters, of which the following is a full, clear, and exact description, reference being had to the accompanying drawings, forming part of this specification.

10 My invention relates to a bolster for railway-cars, the object of my invention being to make a bolster that will combine maximum strength with minimum weight.

15 My invention consists in features of novelty hereinafter fully described, and pointed out in the claims.

Figure I is a perspective view of my improved bolster. Fig. II is a vertical longitudinal section of the bolster, taken on line II II, 20 Fig. III. Fig. III is a horizontal longitudinal section taken on line III III, Fig. II.

The bolster is open at the bottom, except at its ends, and consists of a top 1, vertical side flanges 2, a vertical middle or central flange 25 3, a king-bolt post 4, and spring-seats 5, all cast integral. The spring-seats join the side and central flanges together at the bottom of the bolster and at the ends thereof. On top of the bolster are a center bearing 6 and side 30 bearings 6^a.

By forming the bolster with the three de-

pending flanges it is made very rigid and strong, and none of the flanges require enlargement at their lower edges to give requisite strength to the bolster, as is necessary 35 with a U-shaped bolster or a bolster having a top and two depending side flanges, which greatly facilitates the molding of the bolster. By tying the flanges together at the ends of the bolster the spring-seats are provided and 40 the bolster at the same time is made more rigid without adding much to its weight, and this rigidity is further increased without adding much weight by tying the sides 2 to the post 4 by an integral web 7. 45

I claim as my invention—

1. A bolster, consisting of a top, side flanges, a central flange and spring-seats uniting the bottom of the flanges at the ends of the bolster, all cast integral, substantially as set 50 forth.

2. A bolster, consisting of a top, side flanges, a central flange, spring-seats uniting the bottom of the flanges together at the ends of the bolster, a king-bolt post, and a web connecting the post to the side flanges of the bolster, all cast integral, substantially as set forth. 55

THOMAS M. GALLAGHER.
